UNITED STATES PATENT OFFICE.

GLEN M. DYE, OF MINNEAPOLIS, MINNESOTA, ASSIGNOR TO PHOTOGRAPHIC APPLIANCES CORPORATION, OF MINNEAPOLIS, MINNESOTA, A CORPORATION OF MINNESOTA.

PHOTOGRAPHIC PRINTING AND NUMBERING MACHINE.

1,415,230.

Specification of Letters Patent.

Patented May 9, 1922.

Application filed July 22, 1918. Serial No. 246,117.

To all whom it may concern:

Be it known that I, GLEN M. DYE, a citizen of the United States, residing at Minneapolis, in the county of Hennepin and State 5 of Minnesota, have invented certain new and useful Improvements in Photographic Printing and Numbering Machines; and I do hereby declare the following to be a full, clear, and exact description of the invention, 10 such as will enable others skilled in the art to which it appertains to make and use the same.

My invention relates to photographic printing machines and has for its object to 15 provide simple and efficient means for automatically numbering, or otherwise marking with identifying characters, the prints in such manner that they can be collected and grouped. It is a well established practice 20 with all concerns doing a large business in making photographic prints for numerous customers, to number differently, the prints for the different customers. This has usually been done by hand.

25 My invention provides an adjustable numbering or marking device which is applied to or associated with the platen or presser board in such manner that the photographic print, on its back, will be automatically 30 marked with the order number of the prints that are being taken from the particular negative. The numbering device is made adjustable so that it may be properly re-set for the different orders.

35 The present embodiment of the invention is illustrated in the accompanying drawings wherein like characters indicate like parts throughout the several views.

Referring to the drawings,

40 Fig. 1 is a plan view with some parts sectioned and some parts broken away, showing a photographic printing machine with my numbering device applied thereto;

45 Fig. 2 is a side elevation of the machine shown in Fig. 1, the lower portion thereof being broken away and some parts being sectioned;

50 Fig. 3 is a detail in bottom plan showing the numbering device and immediately associated parts;

Fig. 4 is a vertical section taken through the machine approximately on the line 4—4 of Fig. 1;

Fig. 5 is a detail in vertical section on the line 5—5 of Fig. 4;

Fig. 6 is a transverse vertical section on the line 6—6 of Fig. 4, through the light box;

Fig. 7 is a transverse vertical section taken approximately on the line 7—7 of Fig. 6, 60 some parts being removed and some parts being broken away; and

Fig. 8 shows, in part, the back of a photographic print with the identifying characters marked thereon.

In this preferred embodiment of the machine, a light box 9 is preferably set into an opening in the top of a supporting table 10 with its upper face inclined slightly forward. Within this light box is the usual or 70 any suitable arrangement of electric lamps 11, the leads of which will be later noted.

The top of the light box 9 is preferably 75 in the form of a metal plate 12 formed with a rectangular opening to receive a glass plate 13. This glass plate 13 affords a support for the negative and is preferably seated in the opening of the base plate 12 on the free ends of a plurality of leaf springs 14 that are anchored to the undersurface of said 80 base plate. Here it may be stated that these springs 14 will yield to permit slight movements of the plate 13 under pressure, so as to thereby compensate for differences in 85 thickness, for example, as between glass and film negatives.

So far as this invention is concerned, the mask may be of any suitable construction, but as shown, it is made up of a rectangular portion 15 and two strips 16. The mask 90 strips 16 extend at right angles to each other, co-operate to reduce the size of the light opening through the rectangular mask 15 and are secured at their outer ends to holders 17 which, in turn, are mounted to slide on 95 guide rods 18 supported from the base plate 12 by a post 19.

To press the sensitized paper against the negative and the negative against the glass plate 13 during the printing operation, I 100 provide a suitable platen or presser board which, as an important feature of this invention, is made in two sections which may be designated as the main platen 20 and the supplemental platen 21. The main platen 105 20 has laterally spaced rigid arms 22 that are

pivotedly connected, preferably by cone pointed screws 23 to laterally spaced lugs of a supplemental base plate 24 secured to the main base plate 12.

5 The supplemental platen 21 is pivoted on a pin 25 that projects laterally from a vertical arm 26 that is rigid with the rise from the supplemental base plate 24. For an important purpose which will presently appear, the axis of pivot 25 is offset from and above the axis of the pivot 23. A rocker-acting lever 27 is intermediately pivoted to the fixed arm 26 and one end thereof is connected by a link 28 to a central lug on the top of the main platen 20. The other arm of the rocker 27 is pivotally connected to a sleeve-like head 29 that has threaded engagement with and is adjustable on the upper end of an operating rod 30. This operating rod, at its lower end, is pivoted to one end of a foot treadle 31, suitably pivoted to or mounted on a fulcrum rod 32 supported by the lower portion of the table 10.

25 By reference particularly to Fig. 2, it will be noted that the supplemental platen 21, at its pivot end, has a raised portion 21^a. This arm portion 21^a is adapted to be engaged by a tappet preferably in the form of a roller-equipped stud 33 applied to one arm 22 of the main platen 20 and projects laterally, as best shown in Fig. 1.

30 A coiled spring 34 is anchored at one end and at its other end is attached to the supplemental platen 21. As shown, one end of the said spring 24 is anchored to an eye 35 on the base plate 12, and at its other end, is attached to an eye 36 on said supplemental platen 21.

35 The so-called numbering device, or device for printing identifying characters on the backs of the prints, is preferably made up of a plurality of wheels 37 rotatively mounted on a fixed spindle 38 that is rigidly secured to and projects from a lug 39 on one of the 40 corners of the main platen 20. Preferably, instead of applying the type permanently on the peripheries of these type wheels 37, the type are applied to or formed on small endless rubber bands 37^a that run over the said 45 wheels and under a platen lug 40 that projects laterally from the lug 39, in position to cause the type positioned below said lug 40 to produce the print on the back of the sensitized paper. The sensitized paper in 50 Fig. 8 is indicated by the numeral 41. Of course, the negative will be placed directly upon the mask and the sensitized paper, face downward, will be placed on the negative, this being the printing operation well under- 55 stood.

60 At its extended or free end, the supplemental platen 21 carries an inking pad 42, which, as will presently be noted, delivers the ink onto the type positioned for number- 65 ing the print paper or photographic print.

In Fig. 1, the numeral 43—44 indicates a combined negative clamp and paper guide, the construction of which need not, for the purposes of this case, be considered. The lamps 11 within the light box 9 are connected in a circuit including leads 45 and 45^a that extend from a suitable source of current supply. The lead 45 includes spaced contacts 46 that are insulated from each other, as shown, being attached to insulating blocks 47 secured on the supplemental base plate 24.

65 For co-operation with the spring contacts 46, the operating rod 30 is provided with a sleeve 48 of insulating material, and around this insulating sleeve is provided with a circuit closing contact 49 in the form of a metal sleeve having a split head and clamping bolts 50, by means of which latter said sleeve 49 may be clamped on the insulating sleeve 48 in the proper adjustment for an action which will presently be described.

Operation.

70 Normally, the two-part platen 20—21 will be in the raised position indicated by dotted lines in Fig. 2. The spring 34 normally extends on a line above the axis of the pivot 25 of the supplemental platen 21, and hence, not only forces the supplemental platen upward, but throws the ink pad 42 against the aligned type, and as the type are carried with the main platen, the said spring, at this time, yieldingly holds both platens in the 75 raised position indicated by dotted lines in Fig. 2.

75 In this normal position of the parts, the operating rod 30 is held in a raised position and the circuit closing sleeve 49 will then be above the free ends of the contacts 46, and the latter will then be engaged with the insulating sleeve 48, thus opening the lamp 80 circuit while the piston is raised.

85 When the paper has been properly positioned on the negative, the operator steps on the treadle 31, lowers the rod 30, and positively forces the main platen 20 downward until it comes into contact with the paper and presses the same against the negative. However, it is highly important to note that the 90 initial downward movement of the main platen 20 thus produced, carries with it the supplemental platen 21, and, as the spring 34 will be almost immediately moved to a line below the axis of pivot 25, said spring will 95 throw the supplemental platen 21 down into engagement with the paper almost instantly and in advance of the completion of the paper engaging movement of the main platen. The supplemental platen therefore engages 100 one edge portion of the paper in advance and the main platen follows up and completes the pressing of the paper against the negative. This insures smooth pressing of the paper against the negative and obviates any 105

tendency of rapid movements of the platen to blow the paper out of position, and moreover, permits the operator's hand to remain engaged with the paper until the paper has 5 been thus engaged by the supplemental platen.

- The printing of the number or identifying characters on the back of the sensitized paper takes place as the main platen 20 reaches its 10 final downward position against the paper. Also, as the main platen approximately reaches its lowermost position, the circuit closing sleeve 49 will be engaged with contacts 46, and thereby close the lamp circuit. 15 The lamp circuit will remain closed as long as the main platen 20 is pressed downward to its extreme position, but initial upward movement of the said main platen moves the contact sleeve 40 out of engagement with contact 46 and opens the lamp circuit, so that the light printing operation is 20 timed to correspond to the time that the main platen is held against the paper.

- It is important also to note that when the 25 two-part platen 21-22 is in its lowered position, the spring 34 is far below the axis of pivot 25 so that it will then yieldingly hold the supplemental platen in its lowered or paper pressing positions. 30 The dead center position of the spring 34, that is, the position in which it will, theoretically, not tend to move the platens in either direction, would be aligned approximately midway between the pivots 23 and 25, and 35 when the spring is moved materially in either direction from such so-called dead center position, it will tend to complete the movements of the platen in the one direction or the other and will tend to hold the same in one or the 40 other of the extreme positions.

- When the print has been properly exposed, the operator steps on the treadle 31 and forces the rod 30 upward, thereby positively raising the main platen, as already indicated, 45 and opening the lamp circuit. When the main platen is raised, the supplemental platen 21 does not immediately follow therewith, but is held by a spring 34 pressed against one edge of the print paper to hold 50 the same down while the main platen is making a very considerable part of its upward return movement. As the main platen is raised, the stud 33 engages the arms 21^a of the supplemental platen 21 and positively 55 raises the same therewith through the rest of its upward movement.

- When the platens 20 and 21 move upward, the free end of platen 21 will be projected in respect to the free end or edge of the 60 platen 20, due to the offset points of the pivots 25 and 23, respectively, and hence, when the platen 21 is moved suddenly upward by a spring 24, its ink pad 42 will be thrown suddenly against the aligned number printing type. The two platens 20 and 21 com-

plete their final upward movements together, and at the final upward position, as already indicated, the spring 34 will be on the line slightly upward of the pivot 25, and it will therefore, as already stated, yieldingly hold 70 the said platens in their upturned positions.

Also, the initial upward movements of the platens and operating rod 30 will carry the contact sleeve 49 out of engagement with contact springs 46, thereby again opening 75 the lamp circuit and cutting the lamps out of action. In fact, the sleeve 40 should be so set that the lamps will be cut out of circuit by the initial upward movements of the platens and operating rod and will be cut into 80 circuit only by the latter part of the downward movement of the platen and operating rod.

The so-called platen is what might be designated as a closure plate for the light box. 85 It serves also as a carrier for the so-called numbering devices.

This device which prints either numerals or identifying characters, is herein, for convenience, designated as a numbering device, 90 and to avoid confusion with the term "printing machine" applied to photographic printing machines, which might result if the said numbering device was designated as a printing device, but, in fact, it does print or mark 95 numerals or characters and does so, automatically with a properly timed action in respect to the photographic printing operations.

What I claim is:

1. In a photo-printing machine, having means for supporting a negative and print in position for printing, a pivoted multisection platen for pressing said print against said negative divided on a line at approximately a right angle to the axis of their pivots, and means arranged to actuate said sections differentially.

2. In a photo-printing machine, having means for supporting a negative and print in position for printing, a pivoted multisection platen for pressing said print against said negative divided on a line at approximately a right angle to the axis of their pivots, one of said sections having a limited movement in respect to the other, but movable therewith under further movement, and means for impelling said relatively movable section against the negative in advance of 115 said other section.

3. In a photo-printing machine, having means for supporting a negative, main and supplemental platens working side by side and mounted to oscillate, as entireties, on independent offset local pivots, said supplemental platen having only a limited oscillatory movement in respect to said main platen, and a spring connected to said supplemental platen and anchored at such point that said spring will move from one side to 130

- The other of the pivot of said supplemental platen and will operate to move the latter into contact with the print in advance of said main platen.
5. 4. In a photo-printing machine, having means for supporting a negative, main and supplemental platens working side by side and mounted to oscillate, as entireties, on independent offset local pivots, said supplemental platen having only a limited oscillatory movement in respect to said main platen, a spring connected to said supplemental platen and anchored at such point that said spring will move from one side to 10 the other of the pivot of said supplemental platen and will operate to move the latter into contact with the print in advance of said main platen, and a manually controlled connection to said main platen for 15 imparting movements thereto, to and from the printing position.
5. In a photo-printing machine, having means for supporting a negative and print in position for printing, a pivoted multisection platen divided on a line at approximately a right angle to the axis of their pivots, for swinging movement to raised positions and a number printing device applied to one of said platen sections and an anchoring device carried by another of said sections, said device being arranged to be 20 brought together in the raised position of said sections for automatically imprinting characters on the backs of the sensitized 25 paper.
6. In a photo-printing machine, having means for supporting a negative, main and supplemental platens working side by side and mounted to oscillate, as entireties, on 30 independent offset local pivots, said supplemental platen having only a limited oscillatory movement in respect to said main platen, a spring connected to said supplemental platen and anchored at such point 35 that said spring will move from one side to the other of the pivot of said supplemental platen and will operate to move the latter into contact with the print in advance of said main platen, a number printing device carried by 40 said main platen, and thereby rendered operative to print identifying characters on the backs of the sensitized printing paper, and an anchoring pad 45
- carried by said supplemental platen and moved against said device by the action of 50 said spring.
7. In a photo-printing machine, having means for supporting a negative, main and supplemental platens working side by side and mounted to oscillate, as entireties, on 55 independent offset local pivots, said supplemental platen having only a limited oscillatory movement in respect to said main platen, and a spring connected to said supplemental platen and anchored at such point 60 that said spring will move from one side to the other of the pivot of said supplemental platen and will operate to move the latter into contact with the print in advance of 65 said main platen, a number printing device carried by said main platen, and thereby rendered operative to print identifying characters on the backs of the sensitized 70 printing paper, and an ink pad carried by said supplemental platen and movable against said printing device when said platens are oscillated and are both in raised 75 position.
8. In a photoprinting machine, having means for supporting a negative and print in position for printing, a pivoted multisection platen for pressing said print against said negative, said sections being divided on a line at approximately a right angle to the axis of their pivots, said pivots being out 80 of alignment.
9. In a photoprinting machine, having means for supporting a negative, of main and supplemental platens working side by side, mounted to oscillate as entireties on 85 independent offset local pivots.
10. A photo printing machine having in combination, means for supporting a negative, means for holding a print on said negative, and supplemental means for holding 90 said print on said negative, both of said holding means swinging about offset parallel axes and having closely adjacent sides extending normal to said axes.
- In testimony whereof I affix my signature 95 in presence of two witnesses.
